(57) **CLAIM**

The ornamental design for a container for shoe care products, as shown and described.

DESCRIPTION

FIG. 1 is an isometric view of a first embodiment of a container for shoe care products showing the new design; FIG. 2 is a top plan view of the container for shoe care products shown in FIG. 1;

FIG. 3 is a bottom plan view of the container for shoe care products shown in FIG. 1;

FIG. 4 is a left side elevation view of the container for shoe care products shown in FIG. 1;

FIG. 5 is a right side elevation view of the container for shoe care products shown in FIG. 1;

FIG. 6 is a back elevation view of the container for shoe care products shown in FIG. 1;

FIG. 7 is a front elevation of the container for shoe care products shown in FIG. 1;

FIG. 8 is an isometric view of an alternate embodiment of a container for shoe care products showing the new design; and,

FIG. 9 is a top plan view of a second modified embodiment of the design shown in FIGS. 1–7 showing two containers for shoe care products arranged in a yin-yang configuration, the broken lines are for illustrative purposes only and form no part of the claimed design.

All broken-line illustrations appearing in the drawings are for illustrative purposes only and form no part of the claimed design.
